SWITCH AND SIGNAL CONTROL SYSTEM
FOR RAILROADSNeil D. Preston, Rochester, N. Y., assignor to
General Railway Signal Company, Rochester,
N. Y.

Application January 29, 1938, Serial No. 187,763

37 Claims. (Cl. 246—134)

This invention relates to switch and signal control systems for railroad track layouts, and more particularly to a system of the control panel type in which the operator governs the position of the various track switches and the clearing of the signals for the various routes through the track layout between signal locations by the manipulation of freely movable means associated with the miniature track diagram of the track layout on the control panel.

Generally speaking, and without attempting to define the nature and scope of the invention, the lines on the miniature track diagram representing the railroad track and connecting switches are provided with suitable electric contacts or circuit completion means appertaining to each signal location and to the normal and reverse position of each pair of switch points; and when the operator moves a pencil-like member or stylus on the track diagram along the desired route, the circuit completion means for the various switch points involved in such route are operated to cause automatic operation of the associated switch points to the normal or reverse position as required to establish the route that has been traced or traversed by the operator, the circuit completion means associated with the signal locations being operated by such tracing movement in a way to control the clearing of the signal for train movement over the route in the same direction in which that route was traced. The lines on the track diagram representing the track rails and connecting switch points are preferably in the form of grooves to guide the stylus as it is moved by the operator in tracing the desired route.

In this proposed arrangement, it may be termed a route tracing scheme, the operator is able to set up any route or routes desired between one or more intermediate signal locations for either direction of train movement by merely tracing out the desired route on the track diagram with a stylus or similar device. If there should be alternative or optional routes between two signal locations, the operator can readily trace the one available or desired. Also, if it is desirable for any reason to operate any individual switch to either position without clearing a signal, the circuit completion means associated with the normal and reverse positions of that switch may be individually operated by the stylus to cause operation of that particular switch individually, and without effecting the position of other switches or the indications of signals.

In connection with this route tracing scheme,

it is also proposed in accordance with this invention to provide in a distinctive and arrestive manner suitable indications on the track diagram concerning the operated position of the various switch points, indications of signals, occupied or unoccupied condition of track switches, routes proposed or established and the like, which provide the operator with the necessary information to assist him in his manipulation of the control panel for efficient movement of trains. These indications are preferably given by illuminating portions of track on the track diagram with steady or flashing lights of the same color.

Various other objects, characteristic features, attributes and advantages of the invention will be pointed out as the description progresses.

The accompanying drawings illustrate certain typical and specific embodiments of means characterizing the invention, the parts and circuits being shown diagrammatically and with certain conventional representations with the object of facilitating an explanation and understanding of the nature of the invention, rather than attempting to illustrate the particular organization and arrangement of parts that might be employed in practice. To simplify the illustration, the symbols (+) and (—) are employed to indicate connections to the opposite terminals of a battery or equivalent source of energy, instead of showing all of the wiring connections to the energy source. Also, for convenience the various relays performing like functions are designated by the same letters with distinguishing prefix numbers or letters referring to the different signal locations and switches; and corresponding contacts on these relays are designated by the same reference number.

In these drawings, Fig. 1 illustrates one simple and preferred construction of the control panel for a typical and representative track layout; Figs. 2 and 3 are fragmentary sectional views through the control panel on the lines 2—2 and 3—3 in Fig. 1 to illustrate certain detail features of the preferred construction; Fig. 2A illustrates the freely movable stylus used for tracing routes through the track layout of the miniature track diagram; Fig. 4 is a view of one of the contact bars employed in this control panel arrangement; Figs. 5A and 5B, adapted to be placed end to end, illustrate one specific organization of relays and circuits for establishing the routes for the track layout of Fig. 1; Fig. 6 is a simplified and typical circuit organization suitable for governing operation of a switch machine; Fig. 7 illustrates a suitable organization

of signal control circuits; Fig. 8 is a diagrammatic illustration of the indication means for the track layout of Fig. 1; Fig. 9 shows the control circuits for lighting the lamps of the indication means; and Fig. 10 illustrates a modification of the control circuits for the entrance relays of Figs. 5A and 5B.

In accordance with this invention, it is contemplated that the various pairs of switch points for the single switches and the ends of the crossovers involved in the track layout will be moved and locked by an electrically controlled power mechanism or switch machine. One type of switch machine suitable for this purpose is disclosed in the patent to W. K. Howe, No. 1,466,903, September 4, 1923. It is assumed that the switch machine or equivalent operating mechanism will be provided with suitable point detector contacts reflecting the position and locked conditions of the switch points, preferably by controlling the energization of a switch repeater relay WP in the usual way. It is further contemplated that the signals at the various signal locations of the track layout will be of any suitable type, either semaphore or color-light signals, capable of giving the various distinctive indications for speed signalling in accordance with the usual practice; and since the construction of such signals and their detail control circuits to provide the various proceed, restrictive, call-on and speed indications form no part of the present invention, no attempt has been made to illustrate any particular form of signals and their control circuit organization which may be any one of the well-known types suitable for the purpose. It is also further assumed that the usual detector track sections will be provided for the various switch points in accordance with recognized practice, and further that a suitable arrangement of detector, approach, and sectional rear release locking will be provided for the various switch machines, such as disclosed for example in the patent to O. H. Dicke, No. 2,045,900, June 30, 1936, or the application of A. Langdon, Ser. No. 119,641, filed January 8, 1937.

Control panel.—One characteristic feature of this invention is the way in which the track diagram on the control panel is provided with circuit completion and indication means; and one typical structural organization suitable for this purpose is illustrated in Figs. 1 to 4. This control panel comprises a metallic plate 10 of suitable thickness for the necessary strength and rigidity, to which are fastened by screws 11 or the like flat blocks or pieces 12 of suitable insulating material with an intervening sheet 13 of suitable insulating material. These insulated blocks 12 are shaped and assembled to leave spaces or grooves between their edges representing the lines of the railroad track and the various connecting switch points of the track layout. The edges of these blocks 12 are beveled on the underside as shown in Fig. 2 to hold in place pairs of metallic contact members or bars 14 separated by strips 15 of glass in a manner that will be obvious from the drawings, gaskets 16 of suitable material being preferably interposed between the edges of these glass strips 15 and the contact bars 14.

There is a pair of these contact bars 14 for each signal location, and for the normal and the reverse position of each pair of switch points of a single switch or the ends of a crossover. In

the track layout of Fig. 1, which is representative of those found in practice, the two crossovers 1 and 2 and the single switch 3 provide for train movements over various conflicting and non-conflicting routs for two parallel tracks and a siding or the like between signal locations designated for convenience A, B, etc. For this track arrangement, there is a pair of contact bars such as UA, UB, etc., for each of the signal locations 10 A, B, etc.; a pair of contact bars U1AN and U1BN for the normal position of each end of the crossovers 1; a pair of contact bars U1R for the reverse position of this crossover; and similar pairs of contact bars U2AN, U2BN, U2R, U3N and U3R for the normal and reverse positions of the crossover 2 and the single switch 3.

The contact bars 14 are solid or plated with a material having good electrical surface contact characteristics and which does not readily oxidize or accumulate a film interfering with electrical conductivity. The contact bars 14 of each pair are formed with integral projections or tongues 14a, as best shown in Fig. 4, which project through a hole in the panel plate 10, this hole 20 being preferably lined with an insulating bushing 17. These tongues 14a form terminals to which the connecting wires for the contact bars may be welded or soldered behind the panel with such protecting insulating sleeves (not shown) 30 as may be desired.

This construction of the control panel, which is merely one specific form suitable for the purpose, provides grooves for the portions of track and connecting switch points represented on the track diagram; and these grooves serve to guide the end of a suitable manually movable member or stylus, indicated at 20 in Fig. 2, as it is moved by the operator over the track diagram in tracing or traversing a desired route between signal locations. The freely movable or unmounted stylus 20 is illustrated in Fig. 2A as comprising an insulated handle portion 20a and a contact portion 20b of suitable conducting material attached to the handle and forming the contacting point of the stylus. However, it is to be understood that the stylus may also be entirely of the same suitable conducting material if so desired. As the stylus 20 is moved along the groove of any given route, it makes rubbing contact with the several pairs of contact bars and establishes an electrical connection between the bars of each pair to complete circuits, later described, for establishing the route traced. The ends of the contact bars are preferably beveled to allow free movement of the stylus point into and out of the spaces between the ends of these bars; but if desired the contact bars may be fitted into recesses in the edges of the blocks 12, or insulated spacers may be inserted between the ends of the pairs of contact bars, so as to provide a groove of uniform width for guiding the point of the stylus. These and other modifications in the specific construction illustrated are not material to the invention; and any suitable structural organization may be employed which provides circuit completion means associated with the signal locations and switch points and adapted to be actuated by the manual movement of traversing or tracing the desired route along the track diagram.

The glass strips 15 associated with the different portions of the track diagram are intended to be illuminated to provide indications for the information of the operator. For this purpose,

there is a separate glass strip and an associated miniature lamp for the normal and reverse position of each pair of switch points, and each signal location, and for each of the intermediate or connecting portions of the track as may be necessary to outline or mark out the routes effectively. The glass strips 15 may be longer than the contact bars 14, and preferably are made of such length to have their ends close together to provide an approximately continuous lighted strip or streak for an established route. For certain portions of the track diagram, as between the ends of the facing points for the lower end of the crossover 1 and the switch 3, a glass strip 15 may be used without contact bars 14; and in this instance, the glass strips are held in place between the blocks 12 by thicker gaskets or spacers.

A miniature electric lamp 21 of typical construction is supported on the panel behind each of these glass strips 15, as shown in Fig. 3. When this lamp is lighted, light shines through a hole 22 in the plate 10 against the underside of the corresponding glass strip 15. The glass used for these strips is preferably of a kind, such as that known commercially as Pyrex glass, which affords a high degree of internal reflection from its surfaces; and the under surface of the strip is corrugated or roughened, as indicated at 23, preferably by sand blasting, so that the internal reflection from the under surface is broken up, so to speak, and the entire length of the strip is evenly illuminated when the lamp is lighted.

In the specific form shown, the lamp 21 is supported in a socket 24 by the engagement of the usual contact members on its base with springs 25 secured in the socket 24, which is preferably made of a suitable moulded plastic insulating material. The ends of these springs 25 constitute soldering terminals for the connecting wires. The socket 24 is detachably secured to the back of the panel plate 10, so that it can be readily removed as a whole for lamp replacement by a bayonet type connection between a flange on the base of the socket with ears on a ring 26 fastened to the back of the plate 10, preferably by spot welding as indicated at 27.

It will be noted that this structural organization for mounting and supporting the contact bars 14, glass strips 15, and indicating lamps 21 permits ready replacement of any worn or broken parts, and that all of the wiring connections are back of the panel.

The blocks 12 forming the grooves for the lines on the track layout are preferably cut away adjacent the signal locations to form an opening 28 into which the ends of the stylus can be readily inserted. A cancel button, such as ACN, of the typical spring return push button type is mounted on the panel adjacent each signal location for the purpose later explained. The panel also has for each signal location a symbolic representation, such as AGK, of the signal for that location with a bull's-eye indicating lamp; and letters, numbers, or other marks identifying the various signals, switches, end of detector track sections, and the like, as may be required, are placed on the face of the panel.

Route establishing means.—In accordance with this invention, the movement of the stylus 20 along the grooves in the track diagram by the operator in tracing any desired route causes actuation of the circuit completion means for the corresponding signal locations and switch points; and such completion of electric circuits

energizes relays to control the operation of the switch machines to move their points to the required position, and also to govern the clearing of the signal for train movement in a direction the route is traced. These functions are performed by an organization of relays shown in Figs. 5A and 5B for the typical track layout of Fig. 1; and although the arrangement of crossovers and switches varies in the various track layouts at terminals, junctions, and the like on railroads, the same principles and plan of operation exemplified in the typical circuit organization illustrated in these Figs. 5A and 5B may be adapted and applied to any track layout.

15 This route establishing means comprises an entrance relay, designated NR with a prefix number for the signal location, and a normal and a reverse switch control relay for each pair of switch points, these switch control relays being designated N and R with prefix numbers identifying the particular switch. The normal and reverse switch control relays for a given pair of switch points govern the operation of the associated switch machine to move and lock the switch points in the normal or reverse position. For a crossover there are two normal switch control relays, such as 1AN and 1BN for the crossover 1, but only one reverse switch control relay 1R.

20 It is assumed that the track layout in the field will be provided with detector track sections in the usual way; and in the particular track layout assumed, there are four of these detector track sections designated AT, CT, BT and DT with 25 limits indicated by the conventional representation of insulated joints on the track diagram of Fig. 5A.

25 The electrical circuits characteristic of the route establishing means of this invention can 30 be best understood by describing the principles and plan of operation. As a typical example of the intended operation, assume that the operator desires to move a train from the signal location A to the signal location C. To do this, he inserts the end of the stylus 20 in the opening 28 (Fig. 1) 35 adjacent the signal location A, and moves it along the groove representing the track for the route A—C desired. In making this movement the operator can easily exert a sidewise pressure 40 on the stylus and cause it to follow along the groove for the desired route. For example, in tracing the route A—C, the operator will naturally press the stylus upward in passing by the 45 crossovers 1 and 2; whereas, if tracing a route 50 over these crossovers reverse, a downward pressure 55 would be exerted.

55 During the movement of the stylus in the case of the route A—C assumed, the pairs of contact bars UA, U1AN, U2AN, and UC are electrically 60 connected successively in turn. This causes energization of the entrance relay ANR for the signal location A, and the normal switch control relays 1AN and 2AN for the crossovers 1 and 2, assuming no conflicting routes are established at the time; and the energization of these relays 65 positions the switch points accordingly and cause the signal at location A to indicate proceed as soon as the switches have assumed the proper position, dependent of course upon the presence of other trains ahead or other conditions making it improper to give such a proceed indication.

70 Considering more in detail the circuits by which this result is accomplished, when the stylus connects the pair of contact bars UA, a pick-up circuit for the entrance relay ANR is established

from (+), through relay ANR and back contacts 30 and 31 of relays 1AN and 1R to (-). The relay ANR is held up by a stick circuit from (+), through the front contact 32 of the track relay ATR, contact of the cancel button ACN, front contact 33 of relay ANR, upper winding of relay ANR to (-).

When the stylus engages contact bars U1AN, a pick-up circuit for relays 1AN is established through the back contact 34 of the relay 1R; and with relay ANR energized and its front contact 35 closed, a stick circuit for relay 1AN is established from (+), through front contact 35 of relay ANR, back contact 36 of relay 1R and front contact 37 of relay 1AN, through the winding of relay 1AN, and back contact 34 of relay 1R to (-).

The energization of relays 1AN closes its front contact 40 to connect the stick energy supplied through front contact 35 of relays ANR to what may be termed a route stick circuit through back contact 41 of a slow-release repeater relay ATRP of track relay ATR, wire 5, and a back contact 41 of a similar repeater relay CTRP of the track relay CTR to the back contacts 36 and 37 of the relays 2AN and 2R, so that when the stylus engages the contact bars U2AN and energizes the relay 2AN, this relay is stuck up by a stick circuit in multiple with the relay 1AN.

When the stylus engages the contact bars UC, the entrance relay CNR is not energized, because the relay 2AN was previously energized during the movement of the stylus and breaks at its back contact 30 the pick-up circuit for this entrance relay CNR.

In this way, as the operator traces the route from A to C, the entrance relay ANR for the entering end of this route, and the normal switch control relays 1AN and 2AN for the crossovers 1 and 2 are energized, and are maintained energized by a stick circuit. The route is now established, insofar as the energization of an entrance relay and switch control relays; and the way in which the switch machines and the proper signal are controlled will be later explained.

If the operator wishes to set up the route from C to A, he starts his stylus at the signal location C and traces the route. In this case, the entrance relay CNR is the one which is energized, instead of the entrance relay ANR. The relays 1AN and 2AN are energized as the route is traced and are maintained energized by stick energy supplied through the front contact 35 of the relay CNR and front contact 38 of relay 2AN.

It will be noted that the energizing circuit of the normal switch control relay 1AN includes a back contact 34 of the reverse switch control relay 1R. Similarly, the pick-up circuit for relay 1R includes back contacts 44 and 45 of the normal relay 1AN and 1BN of the same crossover. The same is true for the energizing circuits for the other normal and reverse switch control relays. In other words, the energizing circuit for the normal or the reverse switch control relay for each given switch includes a back contact of the other. Consequently, the operation of the stylus is ineffective to energize the control relay for either position of a switch if the control relay for the other position is then energized; and since every route in conflict with a given route over a switch in one position, say normal, requires that switch to be in the other or reverse position, no switch control relay can be energized by the operation of the stylus to set up a

route in conflict with one already established. For example, the route A-C conflicts with routes A to D over either crossover 1 or 2 reverse and the route A-E; and if any one of these conflicting routes should be established either the relay 1R or the relay 2R is energized, and hence the route A-C cannot be established.

Also, this electrical interlock between the switch control relays of a switch and the maintained energization of a control relay while a route is established prevents any energization of a control relay by careless or accidental movement of the stylus in a way to knock down an established route and put a signal to stop, perhaps in the face of an approaching train.

The circuits for initially energizing and sticking up the normal and reverse switch control relays for the various routes as they may be traced by the operator are similar to those above explained for the typical route A-C; and it would appear to be unnecessary to trace these circuits for all of the other routes.

The circuit completion means on the track diagram and the organization of circuits enables the operator to set up any route desired, for either direction of train movement, by merely tracing or traversing that route on the track diagram with a stylus or equivalent device. In this connection, it can be seen that the operator may trace either one of the optional routes between the same signal locations that the track layout may afford, or may establish through routes past one or more signal locations as he may desire, without the need for any special arrangement of parts or circuits to select between such optional routes or permit setting up through routes in the manner characteristic of the entrance-exit type of switch and signal control system, such as disclosed for example in my prior application, Ser. No. 183,499, filed January 5, 1938. With regard to the through route operation, it should be understood that there is a pair of contact bars, such as the bars UA, for each signal; and if there should be another signal at the signal location A in addition to the one illustrated for movement in the other direction from right to left, there would be a pair of contact bars for such other signal at the left of those shown.

The stick circuits for the normal and reverse switch control relays are arranged in a net work including certain contacts of these relays, which provides in effect a route stick circuit for each route. For example, when the entrance relay ANR is energized, the stick energy through its front contact 35 is extended to the relays 2AN and 2R through the front contact 40 of the relay 1AN if the operator traces a route over the upper end of the crossover 1 normal; but if a route is traced over the crossover 1 in the reverse position, say from A to E, the stick energy supplied through this front contact 35 is extended through the front contacts 36 and 36a of the relay 1R to the relays 3N and 3R, and in turn by a contact 40 on the relay 3N to the relay 2BN, if the route is further traced over the switch 3 normal.

In other words, as the operator traces a route, the normal or reverse switch control relays of the switch points in that route must respond in turn to feed stick circuit energy to the control relays for the next pair of switch points in the route; and if the stick energy is not supplied to a given switch control relay, it drops as soon

as its pick-up circuit is broken by movement of the stylus. Thus, if the operator in tracing a route encounters at any switch another conflicting route, the normal or reverse switch control relay for the intended route at such point of conflict cannot be energized by the stylus, due to the electric interlock above explained; and the stick energy is not carried beyond the point of conflict, so that the control relays for any of the switches in the proposed route beyond such point of conflict will immediately drop, as the stylus is moved away from their corresponding contact bars. In this connection, it should be understood that distinctive indications of an established route are displayed on the track diagram as a result of the energization of normal and reverse switch control relays in the manner later explained, so that the operator has sufficient information to avoid any attempt to set up a route conflicting with one already established; but if he should do so, the arrangement of stick circuits individual to each route avoids sticking up the switch control relays for a route or a portion thereof which is not available, and the resultant confusion in the display of indications or subsequent setting of routes.

These route stick circuits for certain routes also include contacts of the detector track relays and their repeaters, such as the track relay ATR and its repeater ATRP, so that these circuits are interrupted during the movement of the train for the purpose of releasing the N or R switch control relays behind a train, but not ahead of it, during its movement through a route where the rear release approach locking makes it possible to set up another route before the train has entirely cleared the route first established, in the manner presently to be explained.

There may be certain circumstances when the operator wishes to de-energize the entrance relay, after it has been energized and stuck up, and thus release the switch control relays likewise held up, because a route may be established prematurely or by mistake, or an entrance relay may be energized for a route which cannot be completely established on account of conflict with some other route. To take care of this contingency, a cancel button, such as ACN, is located on the track diagram adjacent each signal location, and by operating this button, the operator may break the stick circuit for the corresponding entrance relay ANR, thereby de-energizing the route stick circuit and release any normal or reverse switch control relays that may be held up.

Fig. 10 shows a modification of the control circuits for the entrance relays, such as the entrance relay ANR, in which the need for separate cancel buttons, such as ACN, for each entrance relay is obviated by employing a master cancel switch or key CNB for the whole panel and by arranging the circuits for the entrance relays so that any desired entrance relay may be deenergized by engaging the stylus with the corresponding contact bars while the cancel key CNB is in an operated position. The master cancel key CNB in the normal position shown connects a bus 46 to the positive terminal of the energy supply; and one of each pair of the contact bars for the entrance relays is connected to this bus 46, instead of directly to the positive terminal, as shown in Figs. 5A and 5B. The cancel key CNB when shifted to an operated position connects this bus 46 to the other negative terminal of the energy source through a suitable limiting resistance 47.

In this modification of Fig. 10, each entrance relay (exemplified by the entrance relay ANR) is provided with a single winding and an extra front contact 48 for shunting the back contacts 5 30 and 31 of the switch control relays 1AN and 1R; and after the relay ANR is picked up by engagement of the stylus with the contact bars UA, with the cancel key CNB in the normal position, this relay ANR is stuck up through the front contact 32 of the track relay ATR, and front contact 33 and 48 of the relay ANR. If the operator wishes to de-energize the entrance relay ANR, he operates the master cancel key CNB and engages the stylus with the contact bars UA, thereby shunting the winding of the relay ANR through the resistance 47, which is so proportioned with regard to the resistance of the entrance relay as to reduce the current through the winding of this relay below its drop-away value. The cancel key CNB is then restored to the normal position. If desired this key may be made to be self-restoring. This operation will not affect any other entrance relays that may then be energized. It will be evident that this modification simplifies the construction of the control panel by eliminating the need for individual cancel buttons, such as ACN, for each signal location.

Operation by train movement.—In accordance with this invention the movement of a train through an established route acts to de-energize the entrance relay for that route, but at the same time apply potential to the route stick circuit to maintain energized the normal or reverse switch control relays in that route. The N or R switch control relays in a route are maintained energized while a train is present to provide for the display of suitable indications of track occupancy and also of the portion of the route ahead of the train. Also, the operator is not able to control or pre-condition any of the switches in an established route while it is occupied by a train to assume different positions for another route. In other words, the operator cannot exercise any control to change the position of the switches while a train is passing over or approaching these switches, and thus make the switch locking the sole protection against an improper operation of a switch under or ahead of a train.

Considering this operation and assume as a typical example that the route A—C has been established, the signal at location A cleared, and that a train enters the route. When the train 55 enters the track section AT and drops the track relay ATR, its front contact 32 opens the stick circuit for the entrance relay ANR; but before this relay assumes its de-energized condition and opens its front contact 35, the back contact 32 of the track relay ATR closes and applies potential to the route stick circuit. Also, the track relay ATR closes its back contact 42 in multiple with the back contact 41 of its repeater ATRP, before this repeater is energized by closing back contact 43 of relay ATR, thereby maintaining the route stick circuit closed upon the entrance of the train.

As the train advances through the route A—C in question and enters the track section CT, the track relay CTR closes its back contact 32 and applies potential to the route stick circuit. When the train leaves the track section AT its back contact 32 opens and discontinues the supply of stick current to the relay 1AN, and the back contact 42 of this track relay opens before the

slow-release repeater relay ATRP has time to drop and close its back contact 41, so as to interrupt the supply of stick current to the relay 1AN through the back contact 32 of the other track relay CTR. Consequently, the relay 1AN is released, while the relay 2AN is maintained energized.

This arrangement is employed in the case of the route A—C, because the track layout is such that when the train clears the track section AT, another route from A to E or A to D may be established, without waiting for the train to clear the track section CT. It is assumed that the route locking for the switches will provide the desired rear release for the crossover 1; and the contacts 42 and 41 of the track relay ATR and its repeater ATRP are included in the route stick circuit to release the relay 1AN behind the train, thus permitting energization of relay 1R and also change the display of indications as later described.

If the same route between the signal locations had been set up for train movement in the other direction from C to A, the route stick circuit is broken by the opening of back contact 42 of the track relay CTR before closure of the back contact 41 of its repeater CTRP when the train moves out of the track section CT, thereby releasing relay 2AN, while leaving relay 1AN ahead of the train held up by stick current through the back contact 32 of its track relay ATR.

In a similar way, the continuity of the route stick circuit for the route between the signal locations B and D is governed by the relays BTR and BTRP for train movement from left to right and by the relays DTR and DTRP for train movement in the other direction, in order that the N or R switch control relays may be de-energized behind a train to permit setting up another route. For example, when a train moving from B to D clears the track section BT, the route A to E is available, and it is desirable to de-energize relays 1BN and 3N under these conditions to permit energization of relays 1R and 3R for such route A to E.

In the case of train movement over the crossover 1 or 2 in the reverse position, however, since the ends of these crossovers are ordinarily operated from the same switch machine or by two switch machines controlled alike, the position of the crossover cannot be changed until the train has cleared the detector track sections for both ends of the crossover. Consequently, the route stick circuits for the routes over these crossovers reverse are not provided with relays, such as ATR and ATRP, to open these route circuits as a train moves out of one of the track sections. On the contrary, the reverse switch control relays 1R and 2R are held up by their stick circuits while either of the detector track sections for the ends of these crossovers are occupied. For example, if the route from A to D is set up over crossover 1 reverse, the closure of the back contact 32 of either track relay ATR or BTR is effective to hold up the relays 1R and 3N. However, when the train travelling over this route clears the track section BT, relay BTR co-operates with its repeater relay BTRP to interrupt the route stick circuit and release relays 1R and 3N, thus making it possible to set up a route A—C over crossover 1 normal, or a route A—E over the switch 3 reverse.

Switching control.—Various arrangements of circuits may be employed to control the operation

of a switch machine in the field in response to the energization of its N or R switch control relays; and the switch control circuits shown in Fig. 6 are merely typical of an organization suitable for this purpose. In the arrangement shown in Fig. 6, it is assumed that a switch control relay 1WZ will be governed by a direct unit-wire connection to the switch control relays of the corresponding switch, the circuits being shown for a crossover having two normal control relays 1AN and 1BN. The relay 1WZ is of the usual neutral-polar type; and when the relay 1AN or 1BN is energized, the relay 1WZ is energized over the line wire 59 and a common return with one polarity, say positive; and when the reverse relay 1R is energized, the relay 1WZ is energized with the other polarity. These circuits may be readily traced on the drawing, the symbol CN indicating a common return connection to the mid-tap of a battery.

The normal and reverse operating circuits of the switch machine SM are energized by neutral and polar contacts 51, 52 of the relay 1WZ; and as representative of the locking with which the switch machine will be provided in accordance with the usual practice, these operating circuits are illustrated as including a front contact 53 of a lock relay L, so that whenever this lock relay L is de-energized by the detector, approach and route locking, the operation of the switch machine is prevented.

The switch machine operates a switch repeater relay 1WP in the usual way; and neutral and polar contacts 54, 55 on this relay in co-operation with neutral and polar contacts 56, 57 on the relay 1WZ, control the energization of normal and reverse correspondence relays 1NCR and 1RCR.

For the purpose of controlling the display of indications on the control panel, as later explained, the position and locked condition of the switch has to be indicated in the control office; and for this purpose, there is shown in Fig. 6, switch position indication relays 1WNP and 1WRP for the normal and reverse position respectively controlled over line wires 58, 59 through the polar and neutral contacts 60, 61 of the relay 1WP.

It should be understood that the switch control circuits of Fig. 6 are merely typical or representative of a suitable organization for governing the operation of a switch machine by the energization of normal and reverse switch control relays, and that any other suitable arrangement of circuits may be employed for this purpose.

Signal control.—In accordance with this invention, the signal to be cleared at the entrance end of a route is defined by the energization of an entrance relay, and the route is defined by the energization of the N and R switch control relays, which in turn govern relays WZ for the respective switches, and in turn normal and reverse correspondence relays for these switches.

Fig. 7 illustrates a relatively simple organization of signal control circuits, in which a signal control relay GZ in the field is energized by a direct wire connection 65 and common return by each of the entrance relays. In the various arrangements of circuits for controlling the indications of semaphore or color-light signals there is usually a relay which must be energized to change the indication of the signal from stop and stay to some proceed or less restrictive indication; and in the arrangement shown in Fig.

7, it is assumed that a signal clearing relay GHR will be employed for this purpose.

As a typical example of the operation of the signal control circuits, assume that the operator establishes the route from A to C. In tracing this route, the operator energizes the relay ANR, and the switch control relays 1AN and 2AN. This results in the energization of the relay AGZ at the field; and when the crossovers 1 and 2 assume the normal position, if not already in that position, the correspondence relays 1NCR and 2NCR are energized. This establishes a circuit for energizing the signal clearing relay AGHR for the signal AGK from (+), through relay AGHR, front contact 66 of relay AGZ, front contact 67 of track relay ATR, front contact 68 of relay 1NCR, front contact 69 of track relay CTR, front contact 70 of relay 2NCR and back contact 66 of relay CGZ to (-).

The signal clearing circuits for the other signals are similar to the one just explained, and need not be described in detail.

It should be understood that the organization of signal control circuits shown in Fig. 7 is merely typical of a type suitable for use in accordance with this invention; and various other circuit arrangements involving route relays and the like may be employed, if desired, such as disclosed for example in the patent to Wight, No. 2,027,569, January 14, 1936, or the patent to Larry and Langdon, Patent No. 2,125,242, dated July 26, 1938.

Display of indications.—In order that the operator may govern train movement over the track layout efficiently and correctly, it is important to provide him with suitable and accurate information concerning the position of the switch points, the occupancy of the various detector track sections, indications of the signals, and the like; and also, since the control panel of this invention has no levers or knobs to show by their position what manual operations have been made to set up routes or clear signals, it is also necessary to provide on the control panel suitable indications of the routes attempted or established.

In accordance with this invention, this desired information is displayed by illuminating portions of the track diagram associated with the signal locations, switch points, and other intermediate portions of the various routes, these illuminated portions being also at times intermittently flashed to show occupancy by a train. The indication of switch position is shown by lighting a portion of track on the track diagram adjacent the switch points for the normal or the reverse position which the switch points assume in conformity with the intended route. The position of the switch is not shown on the control board until a route over that switch is attempted, or unless the operator uses the stylus to control the switch individually. The direction of train movement over the route is shown by flashing the lamp in the symbolic representation of the signal when the corresponding signal location has been made the entering point of the route, this flashing indication being changed to a steady lighting when the corresponding signal clears.

The general principles and plan of display of indications are similar to those disclosed in my prior application, Ser. No. 183,499, filed January 5, 1938; and the organization of parts and circuits constituting the present invention is in the nature of a variation or modification of the disclosure in said prior filed application. No claim

is made in this application to anything disclosed in said prior application.

To provide the desired display of indications, the strips of glass 15 (see Fig. 2) above described and their associated lamps are arranged as illustrated in Fig. 8. There is an indicating lamp, such as AK, BK, etc. for a portion of track adjacent each signal location; lamps, such as 1ANK and 1BNK for the portions of track adjacent each switch for the normal position thereof; a lamp, such as 1RK, for the portion of track for each switch or crossover in the reverse position; and other lamps, such as XKa, XKb, and YK for intermediate portions of track between the switch points as may be desired.

In order to give the indicating lamps another distinctive indication, in addition to lighted or extinguished, provision is made to light these lamps intermittently at a relatively slow rate to give a flashing or blinking effect. For this purpose, a flashing bus FB is provided, with suitable means for intermittently connecting it to the energy source. As shown, a contact 74 is operated by a cam 75 continuously driven by a suitable electric motor 76.

The controlling circuits for the indicating lamps are illustrated in Fig. 9; and in addition to the entrance relays, the normal and reverse switch control relays, and track relays involved in connection with the route establishing means, the control circuits for the indication arrangement requires relays, such as AGKR, for indicating the stop or proceed condition of each signal, and relays, such as 1WNP and 1WRP, for indicating the position and locked condition of each switch or crossover.

These indication control circuits involve a repetition or duplication of similar circuits; and a description of the operation for a typical route will be sufficient to make clear the plan and mode of operation of these circuits.

As a typical example of the operation of the indication display means of this invention, assume that the operator sets up the route from A to C. When the relay ANR is energized, the signal indication lamp AGK is connected through the front contact 80 of relay ANR and back contact 81 of relay AGKR to the flash bus FB, so that this signal indication lamp is intermittently flashed to tell the operator that this signal location has been made the entrance end of an attempted route. When the switch control relay 1AN is energized, it closes a circuit through the front contact 82 of the track relay ATR and its front contact 83 and the back contact 84 of the relay 1R to the lamp AK, and also through its front contact 85 to the lamp XKa, thus lighting these two portions of track to tell the operator that the route traced is over the crossover 1 in the normal position. Incidentally, the lighting of these lamps tells the operator that the relay 1AN has been energized and helps him to keep the stylus in engagement with the contact bars U1AN long enough to assure such energization.

The closing of the front contact 85 of relay 1AN also supplies current to the contact 86 of the relay 1WNP; and when the crossover 1 assumes its normal position, if not already in that position, lamp 1ANK is lighted, thus telling the operator that the crossover 1 has assumed the proper position for the desired route. Until this happens, the space between the lighted portions of track AK and XKa is dark, telling the operator that a route over the upper end of the crossover 1 in the normal position has been attempted,

but that this crossover has not yet operated. In this way the operator is able to determine what switches or crossovers, if any, fail to assume the proper position when a route is attempted. The energization of the relay 2AN establishes similar lighting circuits for the lamps CK, XKb, and 2ANK.

In other words, as the operator traces the route, lamps in various portions of the track in this route are lighted to outline or mark out the route attempted; and the portions of track adjacent the switches remain dark until or unless the switches assume the corresponding position. When the route is finally established, insofar as the operation of the switches is concerned, the route is outlined by an approximately continuous streak of light. It will be evident that this leaves on the track diagram a distinctive and effective indication of the routes which have been attempted or completely established; and this information makes it easy for the operator to visualize what routes are available and to avoid attempting to set up a conflicting route. All the operator has to do in effect is to avoid moving his stylus over an illuminated portion of track.

When the signal clears, the signal indication relay AGKR is energized to close its front contact 81 and disconnect the signal indication lamp AGK from the flash bus FB to a steady potential, thereby lighting this lamp steadily to tell the operator that the signal has cleared.

When the train enters the route A-C under consideration, the de-energization of the relay ANR for reasons previously explained extinguishes the signal indication lamp AGK; and the closing of the back contact 82 of the track relay ATR connects the lighting circuits for the lamps AK, 1ANK and XKa to the flash bus FB, thus causing the lamps for these portions of track constituting the detector track section AT to flash or blink. When the train advances into the track section CT, closure of the back contact 82 of the track relay CTR operates in a similar manner to flash the lamps CK, 2ANK and XKb to show occupancy of this detector track section.

When the train leaves the track section AT, the relay 1AN is de-energized for reasons previously explained, and the lamps AK, 1ANK and XKa are extinguished. This tells the operator that the track section involving the crossover 1 is now clear, and is neither a part of an attempted or established route, or occupied by a train, and hence may be included in part of some other route. If, for example, there is a following train which the operator desires to send from A to D, as soon as the lamps AK, 1ANK and XKa go out, the operator may trace this route. When the train leaves the track section CT, the lamps for these portions of track are extinguished in a similar way.

The operation is the same for the other direction of train movement over the route from C to A, except that the signal lamp CGK is the one which is lighted in this case, so that the operator knows that the route marked out by the lighted strip of light is for train movement from right to left.

When the route B to D is traced, and relays 1BN, 3N, and 2BN are energized, the lamp BK is lighted through the front contact 85 of relay 1BN, and lamp 1BNK through this front contact and front contact 86a of the relay 1WNP when the crossover 1 assumes its normal position. The

lamp YK is lighted through the front contact 83 of the relay 1BN and back contact 84a of relay 1R. With relay 3N energized for the route in question, as soon as the switch 3 assumes its normal position, if not already in that position, the lamp 3NK is lighted through the back contact 88 of relay 1R, front contact 89 of relay 3N, and front contact 90 of relay 3WNP. With the relay 2BN energized, the lamp DK is lighted through contacts 83 and 84a of relays 2BN and 2R; and when the crossover 2 is in the normal position, lamp 2BNK is lighted through the contacts 85 and 86a of the relays 2BN and 2WNP. Thus, when the route B to D is established as assumed, this route is outlined or marked out on the track diagram by illuminated portions of track, and when all of the switch points involved in the route assume the required positions, the whole route is shown as a streak of light. In this connection, a lamp similar to the lamp YK may be provided for the portion of track between the ends of the switch 3 and crossover 2 if desired; but it is assumed that the lighting of the lamp YK, together with the lamp DK or EK, as the case may be, will indicate the proposed route clearly enough before the switches respond to cause lighting of the other lamps 3NK, 2BNK in one instance, or 3RK in the other instance.

The operation for lighting the lamps outlining the other routes and indicating the position of the switches therein is similar to that described; and further explanation seems to be unnecessary, except to consider the particular situation where the route is set up over a crossover in the reverse position, and the flashing of the indication lamps for the detector track sections of both ends of that crossover should be maintained, since the crossover is not available for another route until both of these track sections are clear.

Assume for example that the operator sets up the route from A to D over the crossover 1 normal and the crossover 2 reverse in one case and over the crossover 1 reverse and the crossover 2 normal in the other case. In the first case, the flashing of the lamps AK, 1ANK, and XKa may be properly discontinued and these lamps extinguished when the train clears the track section AT with the crossover 1 normal, since the locking of crossover 1 would then be released and it might be desired to use the route from A to E. In the other case, with the crossover 1 set reverse, the flashing of the lamps AK and 1RK should be continued even after the train leaves the track section AT, and until it also leaves the track section BT, since the crossover 1 is locked under these conditions, and the flashing indication should be maintained to tell the operator that such portion of track is not available for a route.

For this reason, the lamps AK, 1RK, and YK are arranged to be controlled differently by the detector track relays depending upon whether the crossover 1 is set for the normal or the reverse position. For the route A to C or A to D over the crossover 1 normal, the lamps AK, 1AN and XKa are supplied with current through the front contact 82 of the track relay ATR alone; and when the train leaves the track section AT and the track relay ATR picks up, these lamps are extinguished. On the other hand, when a route is set up over the crossover 1 in the reverse position, the lamps AK, 1RK and YK and also the lamps 3NK or 3RK and EK, as the case may be, are connected to the flashing bus FB and intermittently lighted if either of the track relays ATR or BTR is de-energized, to give a flashing indica-

tion of the occupancy until both of these track sections are unoccupied and the crossover 1 is free for operation to the normal position for another route.

Considering more in detail the arrangement of circuits for accomplishing this purpose, and assuming a route established from A to E, the lamp AK is lighted by a circuit through the front contact 94 of the track relay BTR, front contact 95 of the track relay ATR, front contacts 96 and 84 of relay 1R. The lamp 1RK is also lighted through the front contact 97 of relay 1WRP when the crossover 1 assumes the reverse position. The lamp YK is lighted by a circuit through the front contacts 94 and 95 of the track relays BTR and ATR, front contacts 96 and 84a of the relay 1R; and with the relay 3R energized for the route A—E in question, current is conducted along this same circuit through the front contact 98 of the relay 3R, back contact 89 of the relay 3N, and front contact 89 of relay 3R to the lamp EK, and also through front contact 100 of relay 3WRP to the lamp 3RK, when the switch 3 assumes its reverse position. When a train enters the track section AT, the circuits for these lamps are connected to the flash bus FB through the back contact 95 of the track relay ATR, the steady potential through the front contact 94 of track relay BTR being cut off; and after the train leaves the track section AT and so long as it occupies the track section BT, these circuits for the lamps are connected to the flash bus FB through the front contact 95 of the track relay ATR and the back contact 94 of the track relay BTR. A similar arrangement of circuits is provided for the crossover 2 in its reverse position.

In this way, when a crossover in its reverse position is used in a route, lamps for the portions of track constituting the detector track sections for both ends of this crossover are maintained flashing until the train has cleared both track sections, and until the reverse control relay for this crossover is deenergized and the crossover unlocked. Consequently, the flashing indication for a portion of track tells the operator in all cases that the crossover in such portion cannot be changed in position, and that he must wait until the lamps for such portion of track are extinguished before another route for the crossover in the different position can be established, thereby enabling him to take advantage of the rear release provided by the route locking.

Two lamps XKa and XKb are preferably employed for the portion of track between the upper ends of the crossovers 1 and 2 in order to outline a proposed route in either direction to the best advantage, separate lamps being employed in separate circuits in this case, because they are in effect associated with different detector track sections and may have to be lighted steadily and intermittently at the same time, which would not be possible with a single lamp. It should be understood, however, that this and other specific characteristics of the disposition of lamps illustrated for the purpose of obtaining the desired display of indications may be modified as desired to fit different conditions.

Individual switch control.—Under certain circumstances it may be desirable for the operator to be able to govern the operation of a given switch from one position to the other without setting up a route or clearing a signal. For example, the operator may wish to free the switch points of snow or some other obstruction, or operate the switch machine for test purposes in

connection with adjustment and maintenance. With a control panel of this invention, the operator can readily operate any switch, as the crossover 1, to either position desired by merely engaging the stylus with the pairs of contact bars U1AN or U1R for the normal and reverse position of the switch, thus energizing the corresponding switch control relays 1AN or 1R and producing the desired operation of the switch machine, assuming no conflicting route is established, and that conditions otherwise make such operation of the switch safe and proper. In the case of such individual operation of the crossover 1, for example, there is no stick circuit energy for holding up the relays 1AN (or 1BN) and 1R; and the stylus must be held in engagement with the pairs of contact bars to maintain these switch control relays and the corresponding relay 1WZ energized until the switch machine has operated to the desired position. In this connection, the indication lamps 1ANK and 1RK of Fig. 9 are lighted when the switch has operated to the desired normal or reverse position.

Also, if the operator should for any reason desire to ascertain the existing position of any switch or crossover of the track layout, without setting up a route, he may do so by engaging the stylus with a normal or reverse pair of contact bars for that switch and noting which indication lamp is lighted. If neither indication lamp can be lighted by this procedure, it shows that the switch is in a mid-stroke position or unlocked.

It can thus be seen that this invention obviates the need for auxiliary or emergency switch levers in a route establishing system for the purpose of obtaining operation of switches individually and without setting up a route or clearing a signal; and also that facilities are provided to enable the operator to ascertain the existing position of any given switch to a degree making it unnecessary to have any normally lighted indication lamps, miniature movable switch points, or the like for this purpose. In the normal operation of setting up a route, the response of the various switches to the desired control is indicated by illuminating or leaving dark a portion of the track adjacent the switch points for their normal and reverse positions.

The particular structural organization of parts and circuits illustrated and described constitutes only one specific embodiment of the invention; and I desire to have it understood that various modifications, adaptations, and additions may be made in the arrangement of the parts and circuits shown and described without departing from the invention.

What I claim is:

1. A switch and signal control system for railroads comprising, a control panel having thereon a miniature track diagram of a railroad track layout, a contact device on said diagram adjacent each of the places thereon corresponding with a signal location and the normal and the reverse position of each track switch, said contact devices belonging to any given route being adapted to be closed successively by an operator as he traces that route, signal and switch control relays momentarily energized by the closure of their corresponding contact devices for governing the operation of the track switches as required to establish a route thus traced and for clearing a signal for train movement in a direction corresponding with the sequence of operation of said contact devices, and track circuit controlled stick circuits for maintaining said re-

lays energized after the initial and momentary energization thereof by the closure of their respective contact devices.

2. In a system for governing the position of power-operated track switches and the indications of associated signals for a railroad track layout, a control panel having guiding grooves constituting a miniature track diagram of the portions of track and connecting switch points of a railroad track layout, a contact device associated with the portion of track adjacent each signal location and the normal and reverse position of each track switch represented by said diagram, a freely movable stylus adapted to be manually moved by an operator along the grooves of said track diagram and guided by the edges thereof to engage momentarily and successively the contact devices associated with the portions of track and connecting switches for any given route traced by the operator, normal and reverse switch control relays for each switch for governing the operation thereof to the normal or reverse position, an energizing circuit for each of said switch control relays closed by the engagement of the corresponding contact device by said stylus, whereby the normal or reverse switch control relays of the switches in a given route traced by said stylus are energized to cause operation of such switches to the position required for such route, and track circuit controlled stick circuits for said switch control relays.

3. A system for governing the position of power-operated track switches and the indications of associated signals of a railroad track layout comprising, a control panel having thereon a miniature track diagram of the portions of track and connecting switches of a railroad track layout, an entrance relay for each signal, a normal and a reverse switch control relay for each switch for governing the operation thereof to the normal or reverse position, a contact device on said track diagram adjacent the portion of track for each signal location and the normal and reverse position of each switch represented on said diagram, a manually movable stylus adapted to engage said contact devices during the movement of said stylus by an operator over the corresponding portion of track, circuit means responsive to the temporary engagement of said contact devices by the movement of said stylus by the operator in tracing a given route for automatically controlling successively the energization of the entrance relay and the switch control relays of the switches for that route, and track circuit controlled means for establishing stick circuits to maintain said relays energized after the initial energization thereof by said stylus.

4. A switch and signal control system for railroads comprising, a control panel having thereon guiding grooves forming a miniature track diagram of a railroad track layout, said grooves being connected at the various switch points and signal locations to form a continuous channel from any signal location to any other signal location on the track layout over the various routes, contact bars associated with said grooves adjacent each signal location, an entrance relay for each signal, a pick-up circuit for each entrance relay connected to the contact bars for the corresponding signal location, other switch control contact bars associated with said grooves adjacent the portions of track corresponding with the normal and reverse positions of each

switch, normal and reverse switch control relays having pick-up circuits connected to the corresponding switch control contact bars, a freely movable stylus adapted to be moved by an operator along said grooves and guided by the edges thereof in tracing any desired route to engage said contact bars and thereby energize successively the entrance relay and the normal and reverse switch control relays of the switches in the traced route, and track circuit controlled stick circuits for said entrance and said switch control relays for maintaining the energization thereof after their initial energization by the movement of said stylus in tracing a route.

5. A switch and signal control system for railroads comprising, a control panel having thereon a miniature diagram of a railroad track layout, contact means on said diagram for each of the places thereon corresponding with the normal and reverse position of each track switch, said contact means for a given route being adapted to be closed by a freely movable member as it is moved by an operator in either direction along the lines of the track diagram in tracing such route, a normal and a reverse switch control relay for each switch for governing the operation thereof to the normal or reverse position, each of said switch controlling relays having an energizing circuit closed by the closure of its corresponding contact means, said energizing circuit for the control relay for each position of a track switch including a back contact of the switch control relay for the other position, and track circuit controlled stick circuits for maintaining said switch control relays energized after the initial energization thereof.

6. In a switch and signal control system of the character described, a control panel having thereon a miniature track diagram of a railroad track layout having switches to provide different routes between signals for governing traffic thereover, a contact device associated with each signal location and the normal and reverse position of each track switch represented on said track diagram, manually operable means acting when moved on said track diagram by an operator from an entering signal location along a given route governed by that signal to close successively and momentarily said contact devices belonging to that route, an entrance relay for each signal location energized by the closure of the corresponding contact device for clearing its corresponding signal when a route governed by that signal has been established, a normal and a reverse switch control relay for each switch for governing the operation thereof to the normal or reverse position, a pick-up circuit for the switch control relay for each position of each track switch including a back contact of the switch control relay for the other position of that switch and energized by the closure of the corresponding contact device, a stick circuit for each entrance relay energized when that relay is picked up until it is automatically opened by the movement of a train passing the corresponding signal location, and stick circuits for said switch control relays including front contacts of the entrance relays for corresponding routes, whereby the tracing of any given route by said manually operable means by an operator energizes and maintains energized the entrance relay and the normal or reverse switch control relays of the switches involved in that route until automatically restored by the passage of a train.

7. A system for controlling the position of

power-operated track switches and the indications of associated signals for governing train movement through the various routes of the railroad track layout comprising, a control panel having thereon a representation in miniature of the portions of track and connecting switches of the railroad track layout, an entrance relay for governing the clearing of each signal, a normal and a reverse switch control relay for each switch for governing the operation thereof to the normal or reverse position, means responsive to the movement of a manually operable device by said operator along portions of track and over the switches represented on said control panel in tracing a given route for successively and temporarily governing the energization of the corresponding entrance relay and switch control relays involved in that route, detector track circuits for the several switches, stick circuits for said entrance relays and switch control relays, and means including said detector track circuits for governing said stick circuits to maintain energization of an entrance relay until a train enters the first detector track section of the route and the energization of the respective switch control relays until such train has moved out of the corresponding detector track sections.

8. In a switch and signal control system for railroads, a control panel having thereon a miniature track diagram of a railroad track layout, a contact device associated with the normal position and the reverse position of each track switch represented on said track diagram, a normal and a reverse switch control relay for each switch for governing the operation thereof to the normal or reverse position, a pick-up circuit for the switch control relay for each position of each switch including said contact device for its own position of its track switch and a back contact of the switch control relay for the other position of that switch, a circuit network of stick circuits for said switch control relays governed by the contacts thereof and including a route stick circuit for each route, and track circuit controlled means for governing said route stick circuits to maintain energization of the switch control relays of those switches in a section of track occupied by a train or in advance thereof and to discontinue the energization of the switch control relays for the switches in a track section behind a train.

9. In a switch and signal control system of the character described for governing train movement through the various routes of a railroad track layout, a control panel having thereon guiding grooves forming a miniature track diagram of the railroad track layout, a contact device associated with each of the portions of track represented on said diagram for the normal and the reverse position of each track switch, a manually movable stylus acting when moved by an operator along the grooves and guided by the edges thereof in tracing a given route to close successively and temporarily said contact device for the normal or the reverse position of each of the switches involved in the route traced, a normal and a reverse switch control relay for each switch for governing the operation thereof to the normal or reverse position and having an energizing circuit controlled by its associated contact device, the energizing circuit for the switch control relay for each position of a switch including a back contact of the switch control relay for the other position, detector track sections for said track layout each including one or more track switches, and stick circuit means for said switch control

relays governed by said detector track sections to maintain energization of the switch control relays for the switches in the track sections of a given route occupied by a train or in advance thereof and to discontinue energization of the switch control relays of the switches in the track section or sections behind the train.

10. In a switch and signal control system of the character described for governing train movement through the various routes of a railroad track layout having power-operated track switches for setting up the routes between different signals, a control panel having thereon a miniature track diagram of a railroad track layout, an entrance relay for each signal location represented on said track diagram, a normal and a reverse switch control relay for each switch for governing the operation thereof to the normal or reverse position, a freely movable member adapted to be moved by an operator along the lines on said track diagram representing the portions of track and connecting switches in tracing a desired route, means responsive to the movement of said member when tracing a given route for energizing the appropriate switch control relays of the switches involved in that route and the entrance relay for the entering end only of said route, said means comprising a pick-up circuit for each entrance relay including a back contact of the normal and/or reverse switch control relay of the switch adjacent the corresponding signal location which must be energized to position that switch for train movement to or from said signal location, whereby the energization of the entrance relay for the exit end of a traced route is prevented by the prior energization of such normal and/or reverse switch control relay during the tracing of that route.

11. A control panel for switch and signal control systems of the route tracing type described comprising, in combination with a supporting plate, of blocks secured to said plate and shaped to form a continuous uninterrupted groove conforming with a miniature track diagram of the portions of track and connecting switches of a railroad track layout, pairs of contact bars electrically insulated from each other and held in said groove by said blocks adjacent the portions of the groove corresponding with each signal and the normal and reverse position of each track switch represented on said diagram, said pairs of contact bars being adapted to be included in a control circuit and to be engaged to close such circuit by the manual movement of a single stylus by an operator along said groove and guided by the edges thereof for any desired route traced by the operator from any signal location to any other signal location of the railroad track layout.

12. In a switch and signal control system of the route tracing type described comprising, a control panel having thereon a miniature track diagram of a railroad track layout, a normal and a reverse switch control relay for each switch for governing the operation thereof to the normal or reverse position and having a pick-up circuit, a manually movable member free and unmounted on said panel, means on said track diagram responsive to the movement of said member along the lines of the track and connecting switches represented on said diagram as the operator traces a route for successively and temporarily closing the pick-up circuits for the appropriate normal or reverse switch control relays of the switches involved in that route, the

pick-up circuit for the switch control relay for each position of a switch including a back contact of the switch control relay for the other position, a circuit network of stick circuits for said switch control relays governed by contacts thereof and including a route stick circuit for each route, said track layout having detector track sections including one or more track switches, and means responsive to the occupancy of each of said track sections of any given route for applying energy to the route stick circuit for that route.

13. In a switch and signal control system for railroad track layouts, a miniature track diagram, a normal and a reverse switch control relay for each track switch of the track layout for governing the operated position of that switch, manually operable means associated with said track diagram for momentarily energizing said switch control relays as required to provide any given route, a network of stick circuits for said switch control relays governed by the contacts thereof and comprising, a route stick circuit for each route, said track layout having detector track sections including one or more switch points, means responsive to the occupancy of any track section in a given route for applying energy to a corresponding point of the route stick circuit for that route, and means effective when a train leaves a track section but not when it enters for temporarily opening such route stick circuit at a corresponding point to cause de-energization of the switch control relays for the switches in the track sections behind said occupied track section.

14. In a switch and signal control system for railroads, a miniature track diagram of a railroad track layout, contact means on said diagram for each signal location and the normal and the reverse position of each switch, a single stylus member adapted to coact with each of said contact means to close a circuit, an entrance relay for controlling the clearing of each signal, a normal and a reverse switch control relay for each switch for governing the operated position thereof, energizing circuits for each of said relays energized by the closure of the corresponding contact means, detector track sections for said track layout, a stick circuit for each entrance relay opened by the occupancy of the detector track section adjacent the corresponding signal, a stick circuit network for said switch control relay including contacts governed thereby and providing a route stick circuit for each route, said route stick circuit for each route being energized by the energization of an entrance relay for that route and being also supplied with energy at a corresponding point by the occupancy of each detector track section in that route in turn as a train travels through the route, and means associated with the route stick circuits for certain routes for temporarily opening said route circuit at a point corresponding with each detector track section in that route when a train leaves that track section but not when it enters, whereby the switch control relays for switches in the rear of a train may be de-energized while those ahead of that train are maintained energized.

15. In a switch and signal control system for railroads, the combination with a miniature track diagram of a railroad track layout, normal and reverse contact devices associated with the switches represented on said track diagram, manually controllable means for closing said con-

tact devices, a normal and a reverse switch control relay for each switch having a pick-up circuit energized by the closure of the corresponding contact device, a plurality of route stick circuits one for each route for maintaining energized the switch control relays of a given route, track circuit controlled means for governing the route circuits of a given route to cause de-energization of the switch control relays for the switches in the rear of a train travelling through a route and maintain energized the switch control relays for switches ahead of that train, and visual indicating means on said track diagram governed by said switch control relays for outlining an established route or portions thereof ahead of a train.

16. In a switch and signal control system, a miniature track diagram of a railroad track layout, normal and reverse switch control relays for each track switch for governing the position thereof, circuit completion means associated with said diagram for governing the energization in succession of said switch control relays to establish any one of the various routes over the track layout, indicating lamps for illuminating linear portions of the represented track disposed adjacent the points on said track diagram corresponding with the signal locations and intermediate portions of track between switch locations, lighting circuits for said lamps including normally open front contacts of said switch control relays to outline a given route upon energization of the switch control relays for that route, detector track circuits for said track layout, a flash bus intermittently energized, and means for supplying to the lighting circuits of the lamps for the portions of track constituting a given detector track circuit a steady potential through the contacts of the associated switch control relays if said track circuit is not occupied and for connecting said lighting circuits to said flash bus while that track circuit is occupied.

17. In a switch and signal control system for railroads, the combination with a miniature track diagram of a railroad track layout, manually governable circuit controlling means associated with the signal locations represented on said track diagram, a manually operable cancel key and a bus common to all signal locations, said bus being connected to one predetermined terminal of an energy source with said cancel key in a normal position and to the other terminal of said source through a shunting resistance with said cancel key in its operated position, an entrance relay for each signal, a pick-up circuit for each entrance relay connected to said bus by the actuation of the corresponding circuit controlling means, and a stick circuit for each entrance relay for supplying current through its winding and a front contact thereof from said predetermined terminal of said energy source, whereby an entrance relay may be manually de-energized by shunting upon actuation of its associated circuit controlling means while said cancel key is in its operated position.

18. In a switch and signal control system for a railroad track layout having a plurality of power-operated track switches for setting up different routes between signals governing traffic thereover, a control panel having thereon guiding grooves forming a track diagram of said track layout, said grooves being connected at the various switch points and extending between points corresponding to the location of the signals in the actual track layout to thereby form

a continuous grooved channel from any signal location to any other signal location of the represented track layout, contact means associated with said grooves at points on said track diagram corresponding to the signal locations and to the normal and reverse positions of the track switches, a freely movable member adapted to be moved along said grooves by an operator in either direction and to be guided by the edges thereof, said member being effective when moved from one end of any route to the opposite end of that route to successively and momentarily close all of the contact means in such route, relays associated with said different contact means, one relay for each such contact means, and each of said relays being energized upon the closure of its corresponding contact means by said freely movable member, circuit means controlled by said relays for causing the power operation of the track switches to establish any route traced by the operator and to clear the signal at the end of such route which will allow train movement over that route in the same direction in which it was traced by the operator, and means for maintaining energized those relays belonging to an established route until a train has passed the respective associated signal or switch.

19. In a switch and signal control system of the character described for governing train movement through a railroad track layout having power operated track switches for setting up various routes between signal locations, a control panel comprising guiding grooves forming a miniature track diagram of said railroad track layout, said grooves being connected at the various switch points and signal locations to form uninterrupted channels extending from any signal location to any other signal location over any available route past one or more signal locations, a contact device on said control panel adjacent each signal location and adjacent each normal and each reverse position of each track switch represented on said track diagram, each of said contact devices being located along the walls of said grooves and parallel thereto, a freely movable stylus member adapted to be moved by an operator along and guided by said grooves in tracing any desired route from an entering signal location to a leaving signal location to thereby engage and momentarily close said contact devices for that particular route, indicating lamps located on said panel so as to illuminate portions of said grooves, route establishing circuit means responsive to the closure of said contact devices along the groove for any given route upon the tracing of that route with said stylus member so as to control the power operation of said track switches to set up that route and to cause said signal to be cleared at the entering end of that route until a train passes such signal, and circuit means controlled by said route establishing means for illuminating those indicating lamps associated with the groove of any given route when the corresponding route is established by said route establishing means.

20. In a system for controlling the position of power-operated track switches and the indications of associated signals for governing train movements through the various routes of a railroad track layout, a miniature track diagram of the railroad track layout, an unmunted manually movable member, contact means on said track diagram adjacent each signal location and each normal and each reverse position of each track switch adapted to be momentarily closed

by said manually movable member during its movement by an operator along the miniature track diagram over any represented route, relays governed by the closure of said contact means for any given route for controlling the positions of the associated switches and the indications of the signals to establish that route traced by the operator, stick circuits for said relays maintaining energized those of said relays picked up for any given route until the passage of a train through that route, and means governed by said relays for illuminating the portions of the track represented on said track diagram to outline the route or routes established.

15. 21. In a switch and signal control system for railroads, a track layout having power-operated track switches for setting up routes between signal locations, normal and reverse switch control relays for each switch for governing the power operation thereof, manually controlled route establishing means for energizing in succession the normal or reverse switch control relay for each of the track switches in any given route to establish that route and to clear a signal for governing traffic thereof, indicating lamps associated with said track diagram adjacent the portions of track corresponding with each signal location and the normal and reverse positions of each of the track switches, and also intervening portions of the represented track between switch locations, a lighting circuit for each of said lamps including normally open contacts operated by the energization of said switch control relays, said lighting circuits effecting the illumination of the indicating lamp for the normal or reverse position of each of the track switches in any given route being established only after such track switch has been operated into a position corresponding with its respective normal or reverse switch control relay then energized, and said lighting circuits effecting the energization of the indicating lamps adjacent the signal locations at the ends of any given route being established and also for said intervening track portions in that route as soon as the switch control relays for the switches adjacent the ends of that route are energized, whereby a route being established is initially outlined on the miniature track diagram and the complete response of the track switches is subsequently indicated by filling in the outline.

22. In a switch and signal control system of the character described for governing train movement through a railroad track layout having power-operated track switches for setting up various routes between signal locations, a control panel comprising a miniature track diagram formed by grooves representing the actual track layout and being connected at points corresponding to the track switches of the track layout to form a continuous groove for any route through the track layout, pairs of contact bars associated with the edges of said grooves at points corresponding with each signal and points corresponding to the normal position and the reverse position of each track switch represented on said track diagram, strips of glass disposed in said grooves for portions of track corresponding with each signal location and each normal position and each reverse position of each track switch, indicating lamps associated with said glass strips and adapted to illuminate the corresponding portion of the miniature track diagram, a freely movable stylus member adapted to be moved by an operator along and

guided by said grooves for tracing any desired route from an entering signal location to a leaving signal location to thereby engage and momentarily close a circuit through each of the pairs of contact bars included in that given route being traced, route establishing circuit means responsive to the closure of the circuits by the stylus member moving along the contact bars for any given route, said route establishing means acting to control the power operation of said track switches to set up that given route and to cause the clearing of the signal at the entering end of that route, and circuit means controlled by said route establishing means for energizing the indicating lamps to illuminate those glass strips included in any given route when the corresponding route is established by said route establishing means.

23. In a switch and signal control system for railroads, a track layout having a plurality of power-operated track switches to set up different routes through the track layout, a normal and a reverse switch control relay for each of said track switches for governing the power operation thereof to the normal and reverse positions respectively, route establishing means manually governable for initially energizing the normal and reverse switch control relays as required to establish any desired route, a network of stick circuits for said switch control relays governed by contacts thereof for completing a route stick circuit corresponding to each route through the track layout when that route is established by the energization of the normal or reverse switch control relays for each of the track switches in such route, detector track circuits associated with said track switches and each track circuit having a track relay, circuit means including a back contact of each of the detector track relays for applying energy to each route stick circuit at points corresponding to the location of the respective detector track circuits in the route whereby a train in passing through a given route applies energy to the route stick circuit for that route at successive points along the route, and circuit means for momentarily opening any given route stick circuit at each point corresponding to two adjoining track circuits, said circuit means including the track relays of the respective detector track circuits.

24. In a switch and signal control system for railroads, a track layout having a plurality of power-operated track switches to set up different routes through the track layout between signal locations governing traffic in opposite directions, said track layout being divided into detector track sections each including one or more of said track switches, an entrance relay for each of said signal locations, a normal and a reverse switch control relay for each of said track switches for governing the power operation thereof to the normal and reverse positions, manually governable route establishing circuit means for initially energizing the entrance relay for the signal location at the entrance to any given route and for subsequently energizing the normal and reverse switch control relays as required to establish that given route, a stick circuit for each of said entrance relays including a front contact of the track relay for the detector track section immediately in advance of the corresponding signal location, a circuit network of stick circuits for said switch control relays governed by contacts thereof for completing a route stick circuit for

each route through the track layout when the normal or reverse switch control relay for each of the track switches in that route is picked up, circuit means for applying energy to the route stick circuit for any given route through a front contact of the entrance relay for the signal location at the entering end of that route, circuit means for applying energy to the route stick circuit for any route at points of such route stick circuit corresponding to the locations of the detector track sections in that route, and means controlled by the track relays for any two adjoining detector track sections for momentarily opening the route stick circuit for any route including such detector track sections at a point corresponding to the point where such detector track sections join whenever a train leaves one or the other of such detector track sections, whereby the entrance of a train into a route deenergizes the entrance relay at the entering end of that route and renders the energization of the switch control relays of the switches in that route dependent upon other energy supplied to the route stick circuit for that route, which route stick circuit receives said other energy through back contacts of the detector track relays as a train passes through such route and which other energy flow to the switch control relays in the rear of such train is momentarily interrupted as the train passes from any track section into the next track section.

25. In a switch and signal control system for railroads, a track layout having a plurality of power-operated track switches to set up different routes through the layout, a normal and a reverse switch control relay for each of said track switches for governing the power operation thereof to the normal and reverse positions, route establishing circuit means manually governable for energizing the normal and reverse switch control relays as required to establish any given route, a circuit network of stick circuits for said switch control relays governed by contacts thereof for completing a route stick circuit for any given route when the normal or reverse switch control relay for each of the track switches in that route is picked up, detector track circuits associated with said track switches and having track relays with contacts for governing said route stick circuits to maintain energization of the switch control relays of those switches having their detector track circuits occupied by a train and those switches in a given route in advance of a train but to discontinue the energization of the switch control relays for the switches in a route after a train has passed beyond their detector track circuits.

26. In a switch and signal control system for railroad interlocking plants, a track layout having a plurality of power-operated track switches to set up different routes through the track layout between signal locations for governing the traffic over such routes, said track layout being divided into detector track sections each section including one or more of said track switches, an entrance relay for each of said signal locations, a normal and a reverse switch control relay for each of said track switches to govern its power operation, manually governable route establishing circuit means for initially energizing the entrance relay for the signal at the entrance to any given route and for subsequently energizing the normal and reverse switch control relays as required to establish that given route, stick circuit means for each of said entrance relays deenergizing

able upon the entrance of a train into the detector track section immediately in advance of the corresponding signal, a network of stick circuits for said switch control relays governed by contacts of said switch control relays for completing a route stick circuit for each route through the track layout when the normal or reverse switch control relay for each of the track switches in that route is picked up, circuit means for applying energy to the route stick circuit for any given route at a point corresponding to the entrance to that route and including a front contact of the entrance relay for the signal at the entrance to such route, circuit means for applying energy to each route stick circuit at points of such route stick circuit corresponding to the locations of the detector track sections in that route, and means controlled by the track relays for any two adjoining detector track sections for momentarily opening the route stick circuit for any route including such detector track sections at a point corresponding to the point where such detector track sections join whenever a train leaves either of such detector track sections, a miniature track diagram of the track layout, a signal indicator lamp on said track diagram for each of said signals, a switch position indicator lamp for the normal and the reverse position of each of the track switches, circuit means for energizing each of said signal indicator lamps when its corresponding entrance relay is energized, and circuit means for energizing the normal or reverse switch position indicator lamp of each track switch when its corresponding normal or reverse switch control relay is energized, whereby the establishment of a route is indicated on said track diagram with the direction of traffic indicated by the illumination of a signal indicator at the entrance to such route, and whereby the passage of a train through a route initially deenergizes a signal indicator at the entrance to the route and subsequently deenergizes the switch position indicators in succession as the train passes beyond the corresponding track switches in the route.

27. In a switch and signal control system for railroads, a track layout having a plurality of power-operated track switches to set up different routes through the track layout between signals for governing traffic over such routes, said track layout being divided into a plurality of detector track sections each including one or more of the track switches, a track diagram of said track layout on a control panel having contact devices located at points on the track diagram corresponding to the locations of the signals and to the normal and reverse positions of each of the track switches represented on the diagram, said contact devices adapted to be manually closed by a freely movable stylus, an entrance relay for each of said signal locations, a normal and a reverse switch control relay for each of said track switches for governing the power operation thereof, circuit means for initially energizing each entrance relay when its corresponding contact device on the control panel is closed, stick circuit means for each of said entrance relays including a front contact of the track relay for the detector track section in advance of the corresponding signal, circuit means for initially and successively energizing the normal or reverse switch control relay for each of the track switches in any desired route extending from any given signal location having its entrance relay picked up, a network of stick circuits for said switch control relays successively closed as

the switch control relays for the switches in any given route are successively picked up, said stick circuits for the switch control relays of that given route receiving energy through a front contact of the entrance relay picked up for that route, circuit means for applying energy to the stick circuits of the switch control relays for any given route whenever one or more of the detector track sections in that route is occupied by a train, and means for deenergizing the stick circuits for the switch control relays of the switches in any given detector track section when that detector track section becomes unoccupied, whereby the switch control relays for the track switches in any given route are successively picked up in order beginning at the entering end of that route and are successively deenergized in the same order as a train passes through that route from the entering end of the route toward the leaving end of the route.

28. In a switch and signal control system for railroads, a track layout having a plurality of power-operated track switches to set up different routes through the track layout between signal locations governing traffic over the routes, said track layout being divided into track sections including one or more of the track switches, a control panel having a track diagram of said track layout located thereon, a signal indicator lamp on said track diagram for each of the signals, a switch position indication lamp for the normal and the reverse position of each of the track switches of the track layout, said switch position indicator lamps being adapted to illuminate linear portions of the represented track, an entrance relay for each of said signals, a normal and a reverse switch control relay for each of the track switches for respectively governing the normal and reverse power operation thereof, manually closable contact means located on said control panel for initially energizing the entrance relay for the signal at the entrance to any given route and for subsequently energizing the normal and reverse switch control relays as required to establish that given route, said switch control relays for the several switches in that route being energized in succession beginning at the entrance end of the route, a stick circuit for each of said entrance relays including a front contact of the track relay for the detector track section in advance of the corresponding signal location, a network of stick circuits for said switch control relays successively closed as the switch control relays for the switches in any given route are successively picked up, said stick circuits for the switch control relays of that given route receiving energy through a front contact of the entrance relay picked up for that route, circuit means for each signal for causing such signal to indicate clear when its corresponding entrance relay is picked up only provided a route extending away from that signal is completely established, circuit means for applying energy to the stick circuits of the switch control for any given route whenever one or more of the detector track sections in that route is occupied by a train, means for deenergizing the stick circuits for the switch control relays of the switches in any given detector track section when that detector track section becomes unoccupied, circuit means for intermittently energizing any signal indicator lamp when its corresponding entrance relay is initially picked up but steadily energizing such indicator lamp when its corresponding signal is cleared, and circuit means for

steadily energizing each switch position indicator lamp having its corresponding switch control relay picked up but intermittently energizing such indicator lamp whenever the corresponding detector track section is occupied by a train, whereby the entrance of a train into an established route deenergizes the signal indicator at the entrance to that route and deenergizes the switch position indicator lamps for the switches in the detector track sections beyond which the train has passed but causing the intermittent energization of the indicator lamps for the track switches in the detector track section or sections in which the train is located while the switch position indicator lamps for the detector track sections in advance of the train remain steadily energized.

29. In a switch and signal control system of the character described, a track layout having switches for providing different routes between signals for governing traffic in opposite directions over such routes, a control panel having thereon a miniature track diagram of the railroad track layout formed as an uninterrupted groove, contact means located on said panel adjacent the groove of said diagram at the points corresponding to the location of said signals, and adapted to be momentarily closed by a stylus-like member as it is moved by an operator along the groove in tracing from the entrance end to the exit end of a route, an entrance relay for each signal, a circuit for energizing each entrance relay upon the closure of its corresponding contact means, a track circuit controlled stick circuit for each entrance relay, and means controlled by the picking up of an entrance relay at the entrance end of a traced route for preventing the energization of the entrance relay at the exit end of that traced route.

30. In a switch and signal control system of the character described, a track layout having switches for providing different routes between signals for governing traffic in opposite directions over such routes, a control panel having thereon a miniature track diagram of the railroad track layout formed as an uninterrupted groove, contact means located on said panel adjacent the groove of said diagram at points corresponding to the locations of said signals and at certain route determining points, said contact means being adapted to be momentarily closed by a stylus-like member as it is manually traced along the groove from the entrance end to the exit end of any available route, an entrance relay for the entrance end of each available route for clearing the signal at the corresponding end when an available route has been set up extending away from such signal location, a pick-up circuit for each of said entrance relays energized upon the closure of said contact means for the corresponding signal location, a stick circuit for each of said entrance relays energizable dependent upon the unoccupied condition of the trackway in advance of the corresponding signal location, route establishing means rendered effective by the picking up of an entrance relay and the closure of the contact means for the route determining points along any available traced route for setting up the corresponding route, and means controlled by the picking up of an entrance relay at the entrance end of any traced route and the response of said route establishing means to set up that route for preventing the energization of the entrance relay at the exit end of such traced route.

31. In a switch and signal control system of the

character described, a control panel having thereon a track diagram of a railroad track layout having track switches to provide different routes between signals governing traffic thereover, a contact device associated with each signal location and with the normal and the reverse position of each track switch represented on said track diagram, a manually operable cancel button associated with each signal location, manually operable means acting when moved over said track diagram by an operator from an entering signal location along any given route governed by that signal to close successively and momentarily said contact devices belonging to that route, an entrance relay for each signal location energized by the closure of the corresponding contact device for clearing its corresponding signal when a route governed by that signal has been established, a normal and a reverse switch control relay for each track switch for governing its power operation to corresponding normal and reverse positions, a pick-up circuit for each switch control relay including a back contact of the switch control relay for the opposite position of that switch and energized by the closure of the contact device for its corresponding position, a stick circuit for each entrance relay energized when that relay is picked up dependent upon the unoccupied condition of the track section in advance of such signal and dependent upon the non-operated condition of its associated cancel button, and stick circuits for said switch control relays including front contacts of the entrance relays for corresponding routes, whereby the tracing of any given route by said manually operable means energizes and maintains energized the entrance relay or the normal and reverse switch control relay included in that route until such route becomes occupied by a train or until the cancel button associated with the entrance signal location has been manually operated.

32. In a switch and signal control system, a track layout comprising parallel tracks connected by a crossover with separate track circuit sections for the opposite ends of said crossovers, a track relay for each track circuit section, switch position contacts respectively closed when said crossover is operated to the normal and reverse position, a miniature track diagram of said track layout, indicating means including lamps for illuminating linear portions of said track diagram representing the different positions of said crossover and the portions of each track common to both positions, circuits energized by the same contact closed when a given one of said track relays is deenergized for lighting the lamp for the common portion of the corresponding track and the lamp for the normal position of the corresponding end of said crossover, said circuit for said normal position lamp including a switch position contact open when the crossover is in the reverse position, and a circuit including another contact closed when said track relay is deenergized and a switch position contact open when said crossover is in the normal position for lighting the lamp of the indicating means for the reverse position of said crossover.

33. In a switch and signal control system for a railway track layout including parallel tracks connected by a crossover, a miniature track diagram of said track layout, a facing point indicator on said track diagram for each end of said crossover including a strip of translucent material and a lamp for illuminating a linear portion of the represented track adjacent and in a

facing point relation to the corresponding end of the crossover, a normal switch control relay for each end of said crossover and a reverse switch control relay for both ends for governing the power operation of both ends of the crossover simultaneously to a corresponding normal or reverse position, manually operable means for selectively energizing said switch control relays as desired to provide a route along either or both of the parallel tracks over the corresponding end of the crossover in the normal position or from one parallel track to the other over the crossover in the reverse position, and lighting circuits for the lamps of said facing point indicators, each lighting circuit being closed by closure of a front contact of the corresponding normal switch control relay or a front contact of said reverse switch control relay, whereby said facing point indicators are separately lighted for routes along the parallel tracks over the respective ends of the crossover in the normal position and are both lighted for a route over said crossover in the reverse position.

34. In a switch and signal control system for a railway track layout having track circuit sections each having a track relay and including one or more track switches operable to provide different traffic routes, a miniature track diagram of said track layout having linear portions of the represented track adjacent and in a facing point relation to each switch provided with a strip of translucent material and an electric lamp for illuminating such facing point track portion, a normal and a reverse switch control relay for each switch acting when energized to govern the power operation thereof to a corresponding normal or reverse position, manually operable means for governing the energization of said switch control relays to provide different traffic routes over said switches, a lighting circuit for the lamp of each of said facing point track portions including normally open contacts of the normal and reverse switch control relays for the corresponding switch and closed when either of these switch control relays is energized, and circuit means governed by the track relays of said track sections for maintaining closed said lighting circuit for the facing point track portion of each switch in an established route occupied by a train until said train has passed out of the track section including that switch.

35. In a switch and signal control system for a railway track layout including track circuit sections of parallel tracks each having a track relay and connected by a crossover, a miniature track diagram of said track layout having separate indicating means for illuminating linear portions of the represented track corresponding respectively with said crossover track and with the track portions adjacent and in a facing point relation to each end of the crossover, a reverse switch control relay for governing the power operation of both ends of said crossover simultaneously to the reverse position, manually operable means for energizing said switch control relay, means governed by said track relays for maintaining said switch control relay energized while a train occupies either of said track sections, and lighting circuits for distinctively illuminating each of said indicating means both including a normally open contact of said reverse switch control relay and selectively controlled by the track relay of either of said track sections, whereby said crossover track and both facing point track portions are distinctively illuminated while a route is estab-

lished over said crossover in its reverse position and while a train occupies either or both of said track sections.

36. In a switch and signal control system for a railway track layout including parallel tracks connected by a crossover, a miniature track diagram of said track layout, a normal indicator and a facing point indicator on said track diagram associated with each end of said crossover by illuminating linear portions of the represented track adjacent that end of the crossover and respectively in a trailing and facing point relation thereto, a reverse indicator for illuminating the crossover track substantially throughout its length, a normal switch control relay for each end of said crossover and a reverse switch control relay for both ends acting when energized to govern power operation of both ends of the crossover simultaneously to a corresponding normal or reverse position, manually operable means for selectively energizing said switch control relays to provide routes over said crossover in its different positions, a lighting circuit for each normal indicator including a normally open contact of the corresponding normal switch control relay, a lighting circuit for the reverse indicator including a front contact of said reverse switch control relay, and a lighting circuit for each facing point indicator closed by closure of normally open contacts of either said reverse switch control relay or the normal switch control relay for the corresponding end of the crossover.

37. In a switch and signal control system for a railway track layout including track circuit sections of parallel tracks each having a track relay and connected by a crossover, a miniature track diagram of said track layout, a normal indicator for illuminating a linear portion of the represented track adjacent each end of the crossover and in a trailing relation thereto, a facing point indicator for illuminating a linear portion of the represented track adjacent each end of the crossover and in a facing point relation thereto, a reverse indicator for illuminating the crossover track substantially throughout its length, a reverse switch control relay for said crossover and a normal switch control relay for each end of the crossover, each of said switch control relays acting when energized to govern power operation of both ends of the crossover to a corresponding normal or reverse position, manually operable means for selectively energizing said switch control relays to establish routes over said crossover in its different positions, stick circuits governed by said track relays for holding up the switch control relay energized by said manually operable means while a train is approaching or passing over said crossover, control circuits for distinctively illuminating each of said indicators, each of said control circuits being governed by front contacts of said switch control relays to render said indicators effective to outline the track included in a route or routes over said crossover by a substantially continuous line of light, said control circuits for said normal indicators and said reverse indicator also including contacts closed only when said crossover is in a corresponding normal or reverse position, and means controlled by said track relays of said track sections for selectively governing said control circuits of each indicator to provide a distinctive illumination of said indicators outlining the route when established and when occupied by a train.
